UNITED STATES PATENT OFFICE

CHARLES F. BRYAN, OF NORTH PLAINFIELD, NEW JERSEY, ASSIGNOR TO R. HOE & CO., INC., OF NEW YORK, N. Y., A CORPORATION OF NEW YORK

WIPER MECHANISM FOR INTAGLIO PLATE PRINTING MACHINES

Application filed October 31, 1929. Serial No. 403,763.

This invention pertains to machines used for printing from an engraved or other intaglio plate, that is secured to a platen and presented first to a mechanism whereby it is inked and then to a wiping mechanism that removes the ink from the surface of the plate which is then ready for the printing operation.

The improvements constituting the invention disclosed herein relate to certain elements of the mechanism for wiping or cleaning the plate, especially the mechanism for rotating the core on which the wiping cloth is wound after it has been used, and the mechanism for holding the padding material which presses the wiping cloth into contact with the plate.

An object of the invention is to provide an improved means for fastening the wiper pad used on a machine for printing from intaglio plates.

Another object of the invention is to provide an improved winding mechanism for rotating the core on which the wiper cloth is wound.

Another object of the invention is to provide an improved winding mechanism for the wiper cloth that will cause the cloth to be fed at a substantially constant rate.

It is also an object of the invention to provide a wiping mechanism of generally improved construction, whereby the device will be simple, durable and inexpensive in construction, as well as convenient, practical, serviceable and efficient in its use.

With the foregoing and other objects in view, which will appear as the description proceeds, the invention resides in the combination and arrangement of parts, and in the details of construction hereinafter described and claimed, it being understood that various changes in the precise embodiment of the invention herein disclosed may be made within the scope of what is claimed without departing from the spirit of the invention.

The preferred embodiment of the invention is illustrated in the accompanying drawings, wherein:

Figure 1 is a side view of a portion of an intaglio plate printing machine with the side

frame broken away, showing the oscillating wiper support and the mechanism for feeding the web of wiper fabric;

Figure 2 is a view of a portion of the wiper support as seen in the direction of arrow 2 of Figure 1;

Figure 3 is a plan view partly in section showing a portion of the wiper support as seen in the direction of arrow 3 of Figure 2; and

Figure 4 is a view partly broken away and partly in section showing the mechanism for controlling the operation of the core on which the wiping cloth is wound after it has been used.

Referring to the drawings 11 and 11' indicate side frames of a printing machine that is adapted to print from an engraved plate 12, that is suitably secured to a platen 12', which is moved on ways suitably supported by means secured to the frame 11 and 11'. One of these ways is shown at 13.

It is generally understood that in this class of printing, the plate is inked by suitable mechanism and the excess ink is then removed from the surface of the plate by one or more wipers which engage the plate as it is moved along the ways.

The wiper mechanism shown herein includes a wiper support indicated generally at 14, which has a body member 15 with projecting lugs 16. One edge of a wiper pad 17, which may consist of felt overlaid with leather, is clamped between bars 18 and 19, which are secured to the lugs 16, while the opposite edge of the pad is similarly clamped between bars 21 and 22, that are secured to tightening members or arms 23, pivoted at 24 in brackets 25, secured to the body member 15. Screws 26, threaded into the arms 23, abut against the side of the body member 15, and provide means for drawing the wiper pad 17 tightly against the face of the body member.

It will be noted that the arrangement of the lugs 16 and the tightening arms 23 is such that the wiper pad is not bent abruptly over the edge of the wiper body. In the forms of tightening mechanism heretofore used the wiper pad is bent at an angle of 90°.

or more and there is a tendency for it to bow away from the face of the wiper support or body member. This difficulty is avoided in the arrangement herein disclosed.

5 The wiper body member 15 is fitted to slide on a cross bar 27 and is held thereto by plates 28 secured to the body 15 by bolts 29. The cross bar 27 is adjustably secured to brackets 31, which are secured to the frames 11 and 11', by bolts 32. Bolts 33 pass through elongated holes 34 in the cross bar and are screwed into the brackets 31. Screw studs 35 are secured to the cross bar and pass through holes in lugs 36, of brackets 31. 10 They are fitted with adjusting nuts 37 and 38, thus providing means for adjusting the pressure with which the wiper bears against the plate 12.

20 Means for oscillating the wiper transversely of the machine, may be provided by a crank not shown, that is connected to a running part of the machine, and operates through suitable connections to rock the arm 39 on its shaft 41, the arm 39 being pivotally connected to an extension 43, formed on the wiper body 15.

25 A roll of wiper fabric wound on a core is shown at 44. The core has a shaft 45, which rests in an open bearing in the frame and is secured by a hinge plate 46 and the clamp screw 47, which when tightened act to restrain the rotation of the roll.

30 The wiper web 48 is led from the roll 44, around the roller 49 which is rotatably supported in bearings in the frames 11 and 11', and around the roller 51, which is rotatably supported in brackets 52, secured to the wiper body 15. The wiper web then passes across the wiper pad 17 and around the roller 53, which is similarly supported in brackets 54, also secured to the wiper body 15. The wiper web is then carried around rollers 55 and 55' supported in the frame and around a control roller 56, which is supported in arms 57 and 57', that are keyed to the shaft 58, which is rotatably supported in the frames 11 and 11'.

35 After passing around the roller 56, the wiper web is wound on the roll 59. This roll is wound about a core that has a shaft 61, that is supported in roller sockets 62, adjustably secured to the side frames 11 and 11'. Adjusting screws 63, provide means for adjusting the sockets 62. An arm 64, is secured to the shaft 58 and is pivotally connected to the link 65, that is similarly connected to arm 66, which is pivoted on the stud 67, secured to the frame 11. The rod 68, has a head 69, pivotally connected to the arm 66, and is provided with a spring 71, which abuts against a popper 72, secured to the frame 11, and thus biases the arm 66 in a clockwise direction, the travel being limited by the lock nuts 73.

40 A rod 74, that is pivotally connected to the two-arm lever 75, is reciprocated by a cam or other suitable means not shown, and is

45 moved in timed relation to other parts of the machine. The lever 75, is pivoted at 76 and pivotally connected to the rod 77, to which a collar 78 is secured. A collar 79, is arranged to slide on the rod 77 and is pressed down by the spring 81, which abuts against the collar 82, that is screwed on the end of the rod. 70

50 The collar 79, is pivotally connected at 83 with a belt crank lever 84, that is pivoted on the stud 85, secured to the frame 11. The opposite arm of the belt crank lever is slotted at 86 for a clamp screw 87, having a nut 88. A link 89, turns on the screw and is also pivotally connected to an arm 91, carrying a pawl 92, which engages a ratchet wheel 93, keyed to a shaft 94, which is rotatably supported in bearings formed by the frame 11 and the bracket 95, which is secured to the frame. The arm 91 is loose on the shaft 94, 85 and oscillation of said arm by the movement of the lever 84, acts to rotate the ratchet wheel 93. A pawl 96, acts to hold the ratchet wheel 93 from turning backwards on the idle stroke 90 of the arm 91. A gear 97, is keyed to the shaft 94 and meshes with the gear 98, secured to the shaft 61.

55 It will be understood that the spring 71 acting through the levers 66 and 64 causes the roller 56 to be pressed against the periphery of the roll 59, and as the material is wound on the roll, its increasing diameter causes the arm 66 to be turned counter-clockwise. The stop 99 on face of the arm 66, provides an abutment for the face 101 of the 100 lever 84, which is pressed against it as shown in Figure 1.

60 In operation, downward motion of the rod 74, causes the collar 78 to engage the collar 79 and push it upward, thus moving the operating face 101 away from the stop 99, and simultaneously turning the ratchet wheel 93, and winding up the fabric on the roll 59. As the roll 59 increases in diameter the stop face 99 is moved toward the left and the lever face 101 moved with it, resulting in decreasing the length of stroke of the arm 91 and in consequence turning the shaft 61 through a smaller arc. 105

65 It will readily be understood that by properly proportioning the parts, substantially the same length of the wiper web may be taken up on the roll at each stroke of the ratchet lever even though the diameter of the roll is constantly increasing in size. 115

70 The distance that the wiper web is advanced by each feeding stroke may be adjusted by moving the screw 87 in the slot 86.

75 What I claim is:

1. In a wiper mechanism of the class described, a roll from which a web of wiper fabric is drawn, a core on which the fabric is rewound into a roll, intermittently operated advancing means to rotate said core, and a control member bearing against the surface 125

of the rewound roll and acting to regulate the movement of the advancing means.

2. In a wiper mechanism of the class described, a roll from which a web of wiper fabric is drawn, a core on which the fabric is rewound into a roll, a reciprocating member acting to rotate said core, a control member bearing against the surface of the rewound roll, and a stop moved by the action of the control member to limit the stroke of said reciprocating member.

3. In a wiper mechanism of the class described, a roll from which a web of wiper fabric is drawn, a core on which the fabric is rewound into a roll, a reciprocating member connected to a ratchet which acts to rotate said core, a roller supported on swinging arms and bearing against the rewound roll, and means governed by the position of the roller, for regulating the motion of the ratchet.

In testimony whereof, I affix my signature.
CHARLES F. BRYAN.
